UNITED STATES PATENT OFFICE.

THOMAS JAMES LITTLE, JR., OF WOODBURY, NEW JERSEY, ASSIGNOR TO WELSBACH LIGHT COMPANY, OF GLOUCESTER CITY, NEW JERSEY, A CORPORATION OF NEW JERSEY.

INCANDESCENT LAMP.

1,031,014.

Specification of Letters Patent.

Patented July 2, 1912.

Application filed January 27, 1912. Serial No. 673,762.

To all whom it may concern:

Be it known that I, THOMAS J. LITTLE, Jr., a resident of Woodbury, Gloucester county, State of New Jersey, have invented a new and useful Improvement in Incandescent Lamps, of which the following is a full, clear, and exact description, reference being had to the accompanying drawings, forming part of this specification, in which—

10 Figure 1 is a vertical section showing one form of lamp having my invention applied thereto. Fig. 2 is a side elevation showing the actuating devices for the gas valve and air shutter or valve. Fig. 3 is a partial sectional view of Fig. 2 at right angles thereto. Fig. 4 is a sectional plan view of the operating mechanism for the valves. Fig. 5 is a perspective view of one form of air shutter or valve, and Fig. 6 is a side elevation of the 20 gas valve and air shutter actuating levers, and the chain pulleys therefor.

My invention has relation to incandescent gas lamps, and more particularly to lamps of the manifold inverted type, although it 25 may be applied to incandescent lamps of other types.

The invention has relation more particularly to a novel means for actuating the gas valve and the air regulating device or shutter so as to supply pure gas to the mantles on lighting, thus positively eliminating all 30 danger of flarebacks.

The precise nature of my invention will be best understood by reference to the accompanying drawings, it being premised, however, that various changes may be made in the details of construction of the several parts, without departing from the spirit and scope of my invention, as defined in the 35 appended claims.

Referring to the accompanying drawings, in which I have illustrated one form of my invention, the numeral 2 designates the casing of an incandescent gas lamp of the type 40 above referred to, and 3 the globe.

4 is the mixing tube, which is shown as extending downwardly and inwardly through an opening inside of the casing 3, having at its lower end a manifold 5, to which the 45 burner tubes 6 are connected.

7 designates the usual inverted mantles connected to the lower ends of the tubes 6.

8 is the gas supply pipe which is connected to the valve casing 9 at its lower end.

10 is the valve spindle which carries a 55 suitable valve within the casing.

11 is the gas jet tube which is connected to the outlet of the valve chamber, and it extends downwardly into the upper end of the mixing tube 4 and is provided with the 60 usual needle valve 12.

13 is the air regulating shutter or valve which is arranged to reciprocate within the upper end portion of the mixing tube 4, in the form of a hollow cylindrical sleeve 65 which, when raised to the position shown in the drawings, is arranged to close the air inlet opening 14 at the upper end of the mixing tube. Projecting outwardly from the air shutter 13 is a pin 15 which passes 70 through an opening in one arm of a lever 16 which is fulcrumed on the valve stem or spindle 10, the other arm 16^a of this lever being connected by a light tension spring 17 with a projection extending outwardly from 75 the valve casing, as indicated at 18.

19 is a two-armed lever, which is fastened to the valve stem 10. Connected to one end of this lever 19 is a valve closing rod 20, and connected to the other end of this lever is a 80 valve opening rod 21. Connected to the same arm 16^a of the lever 16 to which the coil spring 17 is connected is a coil spring 22, which is considerably stronger than the coil spring 17. The other end of this coil 85 spring 22 is connected to a closing chain 20^a at 23.

20^b is a short chain connected to the end of the closing rod 20 and the point 23.

21^a is the opening chain which is con- 90 nected to the end of the opening rod 21 and 21^b is a link connected to the point 23 and the opening chain 21^a.

Assuming the parts to be in the position shown in the drawings, in which both the 95 gas valve and air shutter or valve are closed, and which is the normal position for the valves when the lamp is not lighted, the chain 21^a is drawn downwardly, which will extend the spring 22 at the same time that 100 the rod 21 is drawn to rock the lever into the reverse position from that shown in Fig. 6, to open the gas valve. The pull on this chain, through the medium of the spring 22, will hold the air shutter or valve in its closed 105 position until after the chain 21^a is released, when the spring 17 will rock the lever 16 and move the air shutter or valve 13 down-

wardly in the mixing tube and permit air to enter the mixing tube through the opening 14 adjacent to the gas inlet to said tube. When it is desired to cut off the gas from the lamp the chain 20^a is pulled downwardly, which will first close the air valve or shutter 13 by extending the spring 17; and as soon as the shutter is closed, the spring 22 will be extended by a further downward pull on the chain 20^a and as soon as the slack in the chain 20^b is taken up, the rod 20 will be actuated to rock the lever 19 back to the position shown in the drawings and retain the lever 16 in this position by means of a lug 19^a connected to the lever 19 and which extends at right angles thereto over the end of the lever 16, so that when the gas valve is moved to its closed position the air valve is also held closed, as the power of the spring 17 is not great enough to overcome the friction of the parts to shift the valves.

The advantages of my invention result from the provision of gas and air valves for incandescent gas lamps which are provided with actuating devices arranged to hold the air valve closed when the gas valve is closed. Further from the provision of means for closing the air valve before the gas valve is actuated to cut off the supply of gas to the burner, together with means for holding the air valve in its closed position during the opening movement of the gas valve, which means is arranged to hold the air valve in its closed position until the gas valve actuating mechanism is released.

I claim:

1. In a gas lamp, a mixing tube having an air inlet and a gas inlet, a separate valve for each of said inlets, an operating device connected to the gas valve, an operating device connected to the air valve, and an actuating device connected to the gas and air valve operating devices arranged in extinguishing the light to first move the air valve to its closed position and then close the gas valve; substantially as described.

2. In a gas lamp, a mixing tube having an air inlet and a gas inlet, a separate valve for each of said inlets, an operating device connected to the gas valve, an operating device connected to the air valve, and an actuating device connected to the gas and air valve operating devices and arranged to first close the air valve and then close the gas valve, together with means on the gas valve operating device for retaining the air valve in its closed position; substantially as described.

3. In a gas lamp, a mixing tube having an air inlet and a gas inlet, a separate valve for each of said inlets, an operating device connected to the gas valve, an operating device

connected to the air valve, and an actuating device connected to the gas and air valve operating devices arranged to first close the air valve and then close the gas valve, together with means on the gas valve operating device for retaining the air valve in its closed position, and a spring for opening the air valve when the gas valve is opened; substantially as described.

4. In a gas lamp, a mixing tube having an air inlet and a gas inlet, a separate valve for each of said inlets, an operating lever connected to the air valve, an operating lever connected to the gas valve, flexible actuating devices connected to each end of the gas valve lever, and a resilient connection between the air valve lever and both of said actuating devices and arranged to hold the air valve in its closed position when either of said flexible devices is actuated; substantially as described.

5. In a gas lamp, a mixing tube having an air inlet and a gas inlet, a separate valve for each of said inlets, an operating lever connected to the air valve, an operating lever connected to the gas valve, an actuating device connected to one end of the gas valve operating lever to open the valve, an actuating device connected to the other end of said lever, a resilient connection between the air valve operating lever and both of said devices and arranged to hold the air valve in its closed position when either device is drawn, and means for opening the air shutter when the actuating device for opening the gas valve has been released; substantially as described.

6. In a gas lamp, a mixing tube having an air inlet and a gas inlet, a separate valve for each of said inlets, an operating lever connected to the air valve, an operating lever connected to the gas valve, an actuating device connected to one end of the gas valve operating lever to open the valve, an actuating device connected to the other end of said lever to close the valve, a resilient connection between the air valve operating lever and both of said devices and arranged to hold the air valve in its closed position when either device is drawn, and means on the gas valve lever for retaining the air valve in its closed position when the last mentioned actuating device is released; substantially as described.

In testimony whereof, I have hereunto set my hand.

THOMAS JAMES LITTLE, JR.
